UNITED STATES PATENT OFFICE.

JOHN E. MORGAN, OF BARNSDALL, OKLAHOMA, ASSIGNOR, BY MESNE ASSIGNMENTS,
OF ONE-HALF TO E. D. MCCOY, OF FORT WORTH, TEXAS.

WRENCH FILLER.

Application filed November 6, 1922. Serial No. 599,307.

To all whom it may concern:

Be it known that I, JOHN E. MORGAN, a citizen of the United States, residing at Barnsdall, in the county of Osage and State 5 of Oklahoma, have invented a new and useful Wrench Filler, of which the following is a specification.

This invention aims to provide a filler for a wrench, so constructed that, when there is 10 no occasion for the use of the filler, a portion thereof may be turned backwardly into an inoperative position, it being unnecessary to detach the filler from the wrench.

Figure 1 shows in plan, a portion of a 15 wrench whereunto the device forming the subject matter of this application has been applied; Figure 2 is a section on the line 2-2 of Figure 1.

The numeral 1 marks the head of a 20 wrench 2 of that general sort which is used for handling tools employed in connection with well drilling and maintenance, the wrench having the usual suspension means 14, the opening in the head of the wrench 25 being designated by the numeral 3, and the numeral 4 designating the upstanding reinforcing flange which extends about the opening.

The filler forming the subject matter of 30 this application comprises a plate-like body 5 held by a securing element 6, such as a bolt, on the head 1 of the wrench 2, the body of the filler having a reduced knuckle 7 received between the ears 8 on a wing 9. 35

When the filler is in use, as depicted in 40 the drawings, the wing 8 extends across the upper edge of the flange 4, and the jaws 10 extend downwardly along the inner surface of the flange 4, within the opening 3, the 45 beveled portions 11 of the jaw 10 defining a flared entering throat, whereby the tool or other object to be rotated may be inserted readily between the jaws 10 of the fillers.

When the occasion for the use of the filler 50 has passed, each filler may be swung over, in the direction of the arrow A in Figure 2 into an inoperative position, it being unnecessary to remove the bolt 6, and to de-

tach the filler bodily, from the wrench, in accordance with the present practice. 55

What is claimed is:—

1. A wrench filler comprising a body, and a wing having a jaw disposed substantially at right angles to the wing, and a pivot element connecting the wing and the body, the 60 jaw being disposed approximately parallel to the pivot element.

2. A device constructed as set forth in claim 1, and further characterized by the 65 fact that the jaw is beveled at one end from that surface of the jaw which is remote from the pivot element toward that surface of the jaw which is adjacent to the pivot element.

3. The combination with a wrench including a head having an opening and provided 70 with a flange disposed about the opening, of a filler including a body secured to the head of the wrench, and a wing hingedly connected to the body and extended across the flange, the wing carrying a jaw extended 75 along the flange and disposed at an angle to the wing.

4. In a device of the class described, a 80 wrench having an opening, body members mounted on one surface of the wrench and located on opposite sides of the opening, and wings pivoted to the body members and extended across said surface to the opening, the wings being provided with jaws disposed at an angle to the wings, the jaws being located 85 in the opening at opposite sides of the opening.

5. In a tool wrench having jaws providing an opening between the same, a bushing for said opening comprising an attaching 90 member permanently and rigidly bolted to the upper side of the wrench and provided with an offset hinge member and a bushing member provided with a shank at an angle to said bushing member hingedly connected 95 to said hinge member whereby said bushing member may be swung down into the opening in said wrench and back on top of said attaching member.

In testimony that I claim the foregoing 100 as my own, I have hereto affixed my signature.

JOHN E. MORGAN.

Witnesses:

F. S. HARTMAN,
OTTO GLASER.
